UNITED STATES PATENT OFFICE.

LOUIS GUSTAV FISCHER, OF CAMP HILL, AND MEIER GEORGE HILPERT, OF HARRISBURG, PENNSYLVANIA, ASSIGNEES, BY MESNE ASSIGNMENTS, TO BETHLEHEM STEEL COMPANY, A CORPORATION OF DELAWARE.

APPARATUS FOR OPERATING AIRSHIP-SHED DOORS.

Application filed June 9, 1920. Serial No. 387,777.

This invention relates to mechanism for moving heavy bodies along trackways and it relates particularly to mechanism of this character adapted for use in connection with airship shed doors. The doors for closing the entrances to airship sheds are often of such large size and great weight that it is impossible to move them by manual means within a short period of time, even when two half-doors are used instead of a single large door, to close one end of the shed. As it is essential that such doors are openable and closable quickly, power devices are commonly employed to effect this result, such as motors mounted on the doors in various places, steam engines having winding drums for cables which are secured to the doors, thrust rods or beams with suitable operating means, and other mechanisms of such character.

The various opening and closing mechanisms heretofore designed or suggested have been expensive to install and operate, cumbersome, and unsightly, and objects of this invention are, to provide a mechanism of this class which is comparatively inexpensive, which is compact, conveniently located, and which presents a neat and attractive appearance. More specifically stated the invention resides in novel mechanism for moving an airship shed door which comprises a rack rigidly secured to the door, a pinion or plurality of pinions meshing with the rack and driven by a common power element and, when a plurality of pinions are used, equalizing gearing interposed between the pinions and power element for the purpose of equalizing the forces exerted by the pinions on the rack. This arrangement permits a rack of small width to be used even when great driving force must be exerted thereon, thus saving in the initial cost of the mechanism and the operation and repair costs. One embodiment of the invention will be disclosed in the following description when taken in connection with the accompanying drawings in which:

Figures 1 and 1^a taken together illustrate

in end elevation one of the doors, positioned in front of the entrance of an airship shed and showing in section the pit containing the door operating mechanism;

Figure 2 is a plan view of the heavy base portion of a door positioned in front of an airship shed showing the location of the door operating mechanism, extreme end portions of a second door and a second operating pit being also shown;

Figure 3 is a plan view of the pit containing the door operating mechanism to a larger scale, and showing the mechanism in position;

Figure 4 is a section on the line 4—4 of Figure 3;

Figure 5 is a section on the line 5—5 of Figure 3, but showing the entire mechanism for manually operating the door, a portion of which is omitted in Figure 3.

In the drawings the superstructure of the door and many of its details have been omitted, but it will be apparent that a steel frame and reinforced concrete base door of this character, which may be several hundred feet tall and several hundred feet wide, will be of great weight and, even though mounted upon trucks, will be extremely difficult to move. The doors whether full or half size, are necessarily large inasmuch as it is desired to have the ends of the airship shed entirely unobstructed for the free entrance and exit of airships only slightly smaller in diameter than the width of the shed itself.

In the drawings the front of the shed is indicated at 10 and its center line is indicated by the broken line 11, shown in Figure 2. Two doors are provided, one on each side of the center line, which are mounted upon trucks and adapted to be rolled aside in opposite directions to open the shed entrance for the passage of airships. As these doors are exactly similar only one is completely illustrated in the drawings and this comprises a framework base, preferably counterweighted, and a frame or truss like superstructure to the building face of which is attached the weather proof siding, as diagrammatically

illustrated in Figures 1 and 1^a. The superstructure is indicated at A and the base at B. In Figure 2 it will be seen that the base is substantially rectangular in shape, having two principal truss-like spaced portions 5 C parallel to the front of the shed, and connected by transverse beams and diagonal members. At the four corners of the door are located supporting trucks having wheels 10 12 adapted to roll on trackways 13 which are parallel to the shed front.

Midway between the trackways the door is provided with a heavy girder or beam 14 which is parallel to the trackways and shed 15 front and supports on its lower surface the rack 14' which extends from end to end thereof. Upon the teeth of this rack are exerted all of the forces necessary in moving the door, and the rack and its supporting 20 beam are therefore designed and constructed in a substantial manner.

Located a short distance beyond the side wall of the shed and between tracks 13, is the pit P which contains the mechanism for 25 operating the door. This pit preferably has heavy concrete walls with horizontal wings or extensions, clearly illustrated in Figures 1, 3 and 4, the horizontal wings or extensions providing additional bearing surface so that 30 the reaction of the force exerted upon the door by the machinery contained in the pit will not overturn the foundation upon which the machines are mounted.

The door operating mechanism comprises 35 essentially two pinions 15 each of which meshes with the teeth of rack 14', the pinions being operated by a single motor 16 through pinion 17, differential gearing G, worms 18, 18, mounted on shafts 19, 19, 40 and worm wheels 20, 20, fixed on the shafts 21, 21 on which the pinions 15 are secured.

The differential gearing G comprises the usual ring gear 22, planet gears 23, 23, and sun gears 24, 24 mounted respectively on the 45 shafts 19, 19. The use of this differential gearing insures that each of the pinions 15 will exert the same force on the rack. One particular advantage of this construction is that, by the provision of two pinions acting 50 upon a single rack at different points, it is possible to greatly reduce the necessary width of the rack, which is necessarily of such width that its teeth give the requisite bearing surface for the pinion teeth. By 55 multiplying the number of pinions ample bearing area is provided by a narrow rack. While the use of differential gearing is preferred, for equalizing the pressure of the pinions on the rack this result may be obtained by other means as for instance multiple motors.

Means is provided for operating the mechanism manually in case the motor should be inoperative, for any reason. This means 60 comprises a rotatable shaft 25 provided at

one end with a bevel gear 26 which may be brought into mesh with a bevel gear 27 on the motor shaft when desired, and having at its other end a bevel gear 28 meshing with a bevel gear 29 on the lower end of a capstan 70 stem, the upper part of which is above the ground level and is provided with capstan bars 30 by means of which it may be manually rotated. The motor may be disconnected from the pinion 17 when the doors are 75 being manually moved. This means of operating the doors is much slower than when the motor is employed. If a steam engine or other external motor provided with a winding drum, or a locomotive on a nearby 80 track, is available, a cable may be wrapped around the drum 31 of the capstan, which will be rotated when the cable is unwound.

It will be understood that each of the doors is similar and has similar operating 85 mechanism, and it will be also understood that the design and arrangement of parts of the apparatus may be altered within the limits of the invention and we do not therefore, limit ourselves to the exact form 90 shown and described.

Having thus described the invention what is claimed as new and desired to be secured by Letters Patent is:

1. In mechanism of the class described, 95 the combination with a door having a rack, of means for operating the door comprising a plurality of pinions in engagement with said rack, a source of power, and power transmission mechanism between the source of power and the pinions including means for equalizing the forces exerted by the pinions on the rack.

2. In mechanism of the class described, 100 the combination with a door mounted on rollers and having a rack extending longitudinally thereof, of means for operating the door comprising a plurality of pinions in engagement with said rack, a driving member and differential gearing between the 105 driving member and the pinions.

3. In mechanism of the class described, 110 the combination with a door having a rack, of means for moving said door comprising two pinions rotatably mounted on stationary axles and engaging said rack, a motor, and means operatively connecting said motor and pinions, said means including a device 115 for equalizing the forces exerted by said pinions on the rack.

4. In mechanism of the class described, 120 the combination with a door having a rack secured thereto, of means for moving said door comprising two pinions rotatably mounted on stationary axles and engaging said rack, a motor, and gearing operatively connecting said motor and pinions including differential gearing for equalizing the forces exerted by said pinions on the rack.

5. The combination, with a door, of 125

means for moving the door comprising a rack carried by the door; a plurality of pinions spaced longitudinally of and engaging the rack; a driving member; differential gearing including a pair of driven gears, planet pinions engaging the driven gears, and a carrier for the pinions; means

for connecting the carrier with the driving member; and means for connecting the driven gears to the respective pinions. ¹⁰

In testimony whereof we affix our signatures.

MEIER GEORGE HILPERT.
LOUIS GUSTAV FISCHER.
